CLAIM

I claim the ornamental design for a hospital bed headboard rail cover, as shown and described.

DESCRIPTION

FIG. 1 is a top perspective view of the hospital bed headboard rail cover showing the new design;

FIG. 2 is a bottom perspective view thereof;

FIG. 3 is a top plan view thereof;

FIG. 4 is a bottom plan view thereof;

FIG. 5 is a right end view thereof;

FIG. 6 is a left end view thereof;

FIG. 7 is front view thereof;

FIG. 8 is a back view thereof;

FIG. 9 is a second top perspective view thereof, shown at a reduced scale, and in an environment of use; and,

FIG. 10 is a third top perspective view thereof, shown at a reduced scale, and in a portion of the environment of use. Any differences in appearance of the claimed design in FIGS. 9 and 10 are solely the result of the small scale views. The broken lines in the figures illustrate environment that forms no part of the claimed design.
